UNITED STATES PATENT OFFICE

2,611,524

APPARATUS FOR FILLING AMPOULES

Harry E. Taylor, Baltimore, Md., assignor to Baltimore Biological Laboratory, Baltimore, Md., a corporation of Maryland

Application November 25, 1947, Serial No. 788,050

2 Claims. (Cl. 226—96)

1

This invention relates to the automatic filling and sealing of ampoules and the like, and in particular it concerns an improved apparatus for accomplishing these operations.

The invention relates more particularly to apparatus in which empty sterile ampoules by means of a turn-table or turret are delivered successively, by the intermittent automatic rotation of the turret, to filling and sealing stations, and to a discharge station from which they are automatically dispatched from the apparatus.

A number of attempts have been made to produce automatic ampoule filling and closing machines with varying degrees of success, but prior machines for this purpose have had the drawback that the mechanism is quite complicated, is not readily demountable for cleaning and sterilization and operation thereof results in breakage or charring of a fairly high percentage of the ampoules operated upon.

Accordingly, the primary object of the present invention is the provision of means better adapted to accomplish the described operations. Specifically, the objects attained by the invention may be enumerated as follows:

- (a) Apparatus free from complicated mechanisms and adapted for ease of assembly and disassembly to facilitate cleaning and sterilizing of the parts.
- (b) Avoidance of shattering, crushing, and chipping of ampoules.
- (c) Improved sealing.
- (d) Improved means for positive prevention of the wetting of the necks of the ampoules and subsequent charring when the ampoules are sealed.
- (e) Means for recovery of fluid ejected by the filling nozzle when no ampoule is in position at the filling station.

These and other objects will be apparent from the disclosure.

The invention is illustrated by the accompanying drawings in which:

Fig. 1 is a plan view of the machine.

Fig. 2 is a side elevation of the machine, in part cut away to show elements of the driving arrangement.

Fig. 3 is an elevation of the machine on the side mounting the liquid pumping and measuring device.

Fig. 4 is a vertical section through the valving assembly of the liquid pumping and measuring device.

Fig. 5 is a vertical section substantially on the line 5—5 of Fig. 1, enlarged.

2

Fig. 6 is a horizontal section taken on the line 6—6 of Fig. 5, of parts comprising the filling head assembly.

Fig. 7 is a vertical section on the line 7—7 of Fig. 6, showing parts comprising the filling head assembly in the "up" position.

Fig. 8 is a vertical section similar to Fig. 7 showing the filling head assembly in the "down" or filling position, and

10 Fig. 9 is an enlarged vertical section through an ampoule centering block showing the means for housing the tip of a delivery needle.

Referring to the drawings, 1 indicates a circular turret which is supported by and rotates with 15 a vertical turret shaft 2 journalled in a bearing 2a on the base 2b. The turret is provided along its edge with a plurality of evenly spaced semi-circular retainers or serrations 3 which are cut into its periphery. The serrations are designed 20 to engage and move ampoules 4 placed within them and maintained in position by an annular guideway 5 circumferentially spaced from the periphery of the turret and mounted on a stationary table or platform 6.

25 Ordinarily, the size of the serrations and their spaced relation to the guideway will care for variations in dimensions of ampoules of a given size. That is to say, proper retention of ampoules will be had so long as ampoule size is within a range in which (a) the fit of the ampoules is sufficiently snug to accomplish proper centering at each station, and (b) there is no binding to hinder vertical play or rotation of the ampoules within the serrations. However, to 30 accommodate ampoules of different size range, the apparatus is modified by the substitution of an appropriately sized turret and/or guideway.

The platform 6 serves as a support for ampoules 4, the bases of which slide along the surface of the platform as the turret rotates from 40 the action of an intermittent drive arrangement described below. Rotation of the turret causes the ampoules to describe an annular path defined by the periphery of the turret and the annular guide 5.

45 According to the embodiment of the invention shown in the drawings, rotation of the turret will be counter-clockwise, and ampoules will be fed into the serrations as the latter arrive at or near a point 7. The feeding may be accomplished by hand or preferably by any automatic magazine arrangement, such for instance as that disclosed in U. S. Patent No. 2,383,700 to Barker. The ampoules are then, by the automatic intermittent rotation of the table successively conveyed to (see arrows Figs. 1 and 2) a filling station 8, to

four sealing stations at 9, and to a discharge station 10, the discharge being accomplished merely by camming action of a discharge sweep 11. The sweep is mounted on a receiving table 12 and extends along the platform 6 over to the discharge station 10. Any suitable type of hopper, chute, or packaging arrangement (not shown) may be mounted on the receiving table to collect or carry away the sealed ampoules.

The arrangement of the apparatus assures that ampoules arriving at the feeding, filling, and sealing stations are properly centered for the particular processes to be performed upon them during a dwell period in the operation of the turret.

Power for the operation of the turret and all other moving parts of the apparatus of the invention is supplied by a single variable speed motor 13 of any suitable type which is mounted on the base 2b. I prefer to use an electric motor which is geared at 14 to a drive shaft 15. It is preferable that the motor be of the easily variable constant speed type since variations in viscosity and surface tension of the liquids to be handled require accurate control of filling speeds in order to prevent foaming or development of pressure, etc. In addition, it is necessary to operate at constant speeds in order to obtain proper sealing.

The turret shaft is actuated by suitable means as shown in Figs. 1 and 2. Rollers 16 secured around the periphery of an apron 17 mounted on the turret shaft are engaged by camming grooves 18 of a cam 19 mounted on the drive shaft 15, and continuous rotation of the drive shaft results in intermittent rotation of the turret.

Automatic cut-off and throw-out is provided by means of a safety spring 20 whenever the turret becomes locked against rotation. In such event, driving dog 21 keeps turning with the drive shaft 15 while at the same time compressing the safety spring until face 22 of the cam engages a micro switch (not shown) interrupting current flow to the motor and at the same time disengaging the driving dog 21.

An important feature of the invention is the design and mode of operation of the parts comprising the filling head. Prior workers in the art have adequately discussed the necessity for maintaining a dry delivery needle to avoid wetting of the ampoule necks and subsequent charring by the heat of the sealing flames.

The filling head assembly (see especially Figs. 3, 7 and 8) is supported by an arm 23 rigidly extending from a vertically reciprocating rod 24 mounted in a guide 25 on the platform and extending down through an opening 26 in the platform. The assembly comprises a hollow delivery needle or nozzle 27 protruding vertically downward from its connection with a fluid supply conduit 28 and passing axially through a vertical opening 29 in an ampoule centering block 30 normally supported by a carrier 31.

The filling head assembly of the invention is designed (a) to assure that wetting of the ampoule necks will be prevented and (b) to obviate crushing and chipping of the ampoules.

To accomplish objective (a), the centering block 30 is formed and arranged as follows: The vertical axial opening 29, continuous through the centering block is of varying diameter. As seen in Fig. 9, an extreme upper portion 32 is of a diameter merely sufficient to provide for axial reciprocation of the needle while yet being snug enough to prevent lateral play. Thus the cen-

tering block is prevented from tilting. Adjacent and below the upper portion 32 is an intermediate portion 33 of larger diameter. The function of the portion 33 is to house the tip or delivery end of the needle while the device is in its "up" or normally resting position, and the opening is sufficiently enlarged to prevent any liquid adhering to the needle from contacting the side walls of the opening. A lower conical portion 34 of the opening is shaped to contact and center the ampoule necks prior to the ampoule entry stroke of the needle. By this arrangement, the centering block 30 is supported so that the tip or opening 35 of the delivery needle is maintained out of contact with surfaces of the centering block at all times. That is, in its normal resting position and also when the needle moves downward the point of the needle is never in position to wet the centering block. By this means, subsequent wetting of the upper portions of the needle and of either the interior or exterior surfaces of the ampoule necks is prevented.

Mounted on the platform adjacent the filling head assembly is a vertically adjustable stop 36 which determines the maximum descent of the centering block on the downward movement of the filling head. Directly below the point of the needle an opening 37 is disposed in the platform. This opening, in conjunction with spillway trough or conduit 38 positioned beneath it, functions to collect any discharge made by the needle when no ampoule is in position to receive the discharge.

In operation, the entire filling head reciprocates vertically according to the piston-like motion of the rod 24. The assembly is always at its up or lifted position while the turret is in motion and lowers to automatically center and fill any ampoule in position at the filling station when the turret comes to rest. Upon completion of the filling operation, camming action (to be described below) influences the filling head (by means of the piston rod 24) to return to the up position prior to resumption of rotation by the turret.

As the assembly comes down, the rigidly supported carrier and the centering block move with it. The centering block contacts the tip of the neck of the ampoule which it centers by the conformity of the surface of the recess 34 in the block. The block remains supported by the tip of the ampoule as the device continues its downward movement, passing the filling needle well into the neck of the ampoule. The lowermost point of descent of the assembly is determined by cam 39 and when that point is reached, actuation of automatic pipetting machine 40 takes place to deliver the desired amount of liquid through the needle into the ampoule. The assembly then returns to its up position, the centering block being picked up by the carrier 31 on its upward journey.

Another feature of the invention is the means for prevention of wetting of the centering block when—as is likely to happen occasionally—no ampoule is in position at the filling station at the time fluid is ejected by the nozzle. The arrangement for accomplishing this is shown particularly in Figs. 7 and 8. The stop 36 is adjustable as to height by means of a set screw 41 (Figs. 1 and 3). The stop is positioned to contact and support the centering block, holding it from further downward motion when the block has reached a point below that at which it would have contacted an

ampoule had the ampoule been in position. Thus, the block is held above the level of ejection by the needle and will not be wet by the fluid, and consequently the exterior surfaces of the necks of successive ampoules will be maintained dry.

In addition to the height adjustment provided for the stop 36, the vertical position of the arm 23 on the rod 24 may be changed by means of set screw 42.

It is to be noted that the upward stroke of the piston rod is promoted by lever arm 43 actuated by the cam 39 mounted on the drive shaft 15, while the downward stroke results merely from free fall of the piston rod and filling head when action of the cam 39 on the arm 43 causes lowering of the arm. That is to say, the downward motion is merely the sliding of the assembly from its own weight when its support (the lever arm 43) is lowered. This fact is of utmost importance to the accomplishment of objective (b) (mentioned above), e. g., the ability of the device to minimize crushing and shattering of ampoules which invariably occur when there is mechanically propelled relative motion between ampoules and filling devices.

Further, it is an essential of the invention that no force other than that of gravity acts upon the centering block in its downward motion. Thus, breakage and chipping of ampoules is further reduced.

Fluid is delivered to the filling needle by the conduit 28 from the automatic pipetting device 40 capable of delivering precise amounts in quantities according to the predetermined setting of an adjustable eccentric shank 44 which causes actuation of pump 45. This automatic pipetting machine is substantially as described in U. S. Patent No. 2,148,899 to Carski and Brewer but modified insofar as valve pin 46 (see Fig. 4) of output valve 47 is provided with a groove 48 by means of which sufficient suction is established in delivery conduit 28 prior to closure of the output valve to insure that any drop hanging at the end of the delivery nozzle (subsequent to the completion of fluid ejection into an ampoule) will be drawn up into the nozzle. The valve pin 46 is the equivalent of the guide piece designated as 51 in the Carski and Brewer patent.

With reference to Figs. 1-4, the operation of the automatic pipetting assembly may be briefly described as follows:

The assembly being mounted on a support 49, a handle 50 secured to pump plunger 51 has position on eccentric shank 44 which rotates with cam shell 52 mounted on the drive shaft 15. Rotation of the drive shaft thus actuates reciprocation of the plunger 51 in cylinder 53, which sways with a valve block 54 on its supporting pin shaft 55. As the plunger moves downwardly, it sucks in fluid from a primary container (not shown) through conduit 56 and through intake valve 57 and incidentally forces output valve pin 46 into its seat 58.

The liquid flows into and fills the cylinder 53 with the desired amount determined by the setting of adjustable shank 44 on the cam shell 52. On the return stroke, the plunger forces the liquid through the output valve 47 and incidentally closes the intake valve 57. Upon completion of the outlet stroke, the intake stroke is of course again begun, opening the intake valve and closing the outlet valve. However, as the sealing closure of the outlet valve is in progress, the groove 48 in the valve pin 46 allows passage of fluid from the conduit 28 back into the valve block 54 as a

result of suction occurring from the commencement of the intake stroke. As a result of the fluid return from the conduit, any drop hanging at the end of the delivery nozzle is drawn back up into the nozzle, thus avoiding wetting of parts of the filling head assembly and promoting accuracy of delivery by the pipetting machine.

The eccentric shank 44 may be associated with the cam shell 52 in conformity with the arrangement disclosed in the above-mentioned Carski and Brewer patent, or by any suitable method. In the accompanying drawings, the shank 44 is shown as rigidly secured in offset position to a post 59 which is mounted at any predetermined point on the face of the cam shell 52. Thus the cam shell may be calibrated, having a number of points for attachment of the post 59, each point being labeled in terms of pump output.

The ampoule sealing unit consists of an assembly of two oppositely disposed rows 60 and 61 of four burners each, the burner rows being spaced apart to allow passage of the ampoules between them. Each pair of oppositely positioned burners forms a sealing station having a specific function, and the flame jet from each burner of a pair is focused to fall on the neck of the ampoule at the same level as the flame of the opposite burner.

The sealing unit is of course positioned in the path of the ampoules leaving the filling station, and the entire unit is vertically adjustable by means of a screw-threaded device 62 to care for various sized ampoules.

The arrangement of the burners for the sealing operation is of importance. Each of the burners 63 comprising the pair nearest the filling head assembly form the first sealing station. The flames from these burners are adjusted to heat the container neck only sufficiently to expand and expell the air or gases which are present. This is to prevent bulging of the glass at the ampoule tip when the seal is subsequently completed. Further, when the ampoule is later cooled, the result of the work done at the first station will be the formation of a partial vacuum and a vacuum seal.

At the second station, comprising the pair of burners 64, the burners are adjusted at an angle which will direct the flames upward to prevent overheating of the contents of the glass containers. The flames heat the glass tip of the ampoule neck intensely so as to melt the glass and thus cause it to drop below the point of the flame. The flames from the third pair of burners 65 are directed upon only the tip of the melted portion in order to complete the sealing of the neck and seal any unclosed ampoules. The pair of burners 66 located farthest from the filling station, is provided to retard rapid cooling and thus anneal the heated glass.

It will be noted that the position of the burners is important, since the angle of the flames emitted by each burner is critical to the proper performance of the particular function of that burner.

During the preheating, sealing, and annealing it is necessary to rotate the ampoules because of the great variations in the alignment of ampoule tips to the ampoule bodies. When the ampoules are rotated, all desired portions of the tip are brought into contact with the sealing flames and a seal of even and regular shape is produced.

Rotation of the ampoules is provided by continuously rotating discs or turn-tables 67, one

of which is set into the platforms at each sealing station. The discs 67 are mounted on shafts 68 driven by suitable gearing from the shaft 15. The top surface of the rotating discs should be of cork or similar composition which will provide sufficient friction against the ampoule base to cause the ampoule to rotate, and it is obvious that proper operation of the equipment dictates that the surface of the cork be flush with the surrounding surface of the platform.

It is obvious from the disclosure that the apparatus of the invention is comparatively simple, practical, and extremely useful. In providing for the automatic filling and sealing of ampoules, the invention exhibits functional improvements over the prior methods and apparatus in that it provides (a) means for reducing to a minimum the troublesome and dangerous crushing, shattering, and chipping of ampoules, (b) means for positive prevention of wetting the parts of the filling assembly and subsequently the ampoule necks, (c) means for producing a superior seal, and (d) means for recovery of liquid lost when an ampoule is not in position at the filling station.

I claim:

1. Automatic ampoule filling apparatus comprising a drive shaft, a transmission actuated by said drive shaft, ampoule conveying means intermittently actuated by said transmission, an ampoule filling assembly actuated by said drive shaft, and means adapted to supply said ampoule filling assembly with measured amounts of fluid comprising a cam shell mounted on said drive shaft, means for varying the camming effect of said cam shell, a plunger pump actuated by said cam shell, a fluid conducting valve block associated with said pump, a fluid inlet mounted in

10 said block, a fluid intake valve actuated by said pump and mounted in said inlet, a fluid outlet conduit mounted in said block, a conduit connecting said fluid outlet with said ampoule filling assembly, a fluid output valve actuated by said pump and mounted in said outlet, a valve pin associated with said output valve, and a groove disposed in said valve pin adapted to permit the flow of fluid from said conduit to said compartment during closing movement of said output valve.

2. Automatic fluid pipetting apparatus adapted for association with automatic ampoule conveying and filling equipment comprising a cam shell 15 adapted to be mounted on a drive shaft for said equipment, pumping means actuated by said cam shell, and valving means associated with said pumping means comprising an inlet valve assembly, an output valve, an output valve pin, and a fluid by-pass groove formed in the point of said valve pin.

HARRY E. TAYLOR.
